UNITED STATES PATENT OFFICE.

OTTO F. FOGELSTRAND, OF KENSINGTON, CONNECTICUT, ASSIGNOR TO
HART MANUFACTURING COMPANY, OF SAME PLACE.

DESIGN FOR CEILING-HOOK.

Specification forming part of Design No. 5,699, dated March 19, 1872.

To all whom it may concern:

Be it known that I, OTTO F. FOGELSTRAND, of Kensington, in the county of Hartford and State of Connecticut, have invented and produced a new and original Design for a Ceiling-Hook, of which the following is a specification:

The nature of my design is fully represented in the accompanying engraving, to which reference is made.

An octagonal flange surmounts this device, from which flange extends downward the body of the hook proper, the same being bifurcated

at the lower end, and formed into two hooks with angular bends, as shown. The under side or face of the octagonal flange and the sides of the hook are bordered by a raised ledge, inside of which are raised ornamental figures, as shown.

I claim as my invention—

The design for a ceiling-hook, substantially as shown.

OTTO F. FOGELSTRAND.
